VALVED COUPLING FOR GAS WELLS

George E. Van Voorhis, Dilliner, Pa.

Application December 10, 1934, Serial No. 756,773

1 Claim. (Cl. 251—3)

My invention relates to natural gas-wells, and is found in a coupling for use in such wells. Notice is given of my co-pending application Serial No. 73,052, filed April 7, 1936.

5 Ordinarily, a gas-well includes a tubular casing which extends from the earth's surface downward and into communication with the "upper" sand—the first gas-yielding stratum reached during the drilling of the well. When in the operation 10 of the well the yield or "pay" of the upper sand becomes low, the well is drilled deeper, down to the next lower gas-bearing stratum. Within the outer casing a line of tubing is run to this so-called second sand, and the yield of the well 15 then comprises the gas delivered by the second sand, plus the gas delivered by the upper sand. Usually water is present in the gas-bearing strata, and such liquid drains into the passages through which the yielded gas enters the tubing and 20 casing. The liquid which drains from the second sand and floods the entrance to the inner tubing may be removed in well-known manner, by operating a bailer within the tubing, but the liquid draining from the upper sand into regions 25 between the tubing and the casing is not always accessible to the bailer, and the removal thereof presents a problem. More particularly my invention relates to improvements in a coupling providing for flow between the inner and outer 30 passages of a gas-well.

In the accompanying drawing Fig. I is a diagrammatic, sectional view of a gas-well, showing the inner tubing of the well provided with a special, adjustable coupling in which the invention is realized; Fig. II is a fragmentary view 35 of the well, showing to larger scale the coupling in alternate position of adjustment; and Fig. III is a view of the coupling in side elevation.

In Fig. I of the drawing the reference numeral 40 1 indicates the upper sand, and 2 the second sand of the well W. In accordance with usual practice the outer casing 3 of the well is sealed in a casing head 4 at the earth's surface and extends downward therefrom and into communication with the upper sand 1. The inner tubing 5 of the well is also sealed in casing head 4 (cf. the casing head gland 6), and extends within the casing 3 downward to or to a point below the second sand 2. The foot 50 of the tubing 50 5 is perforate, and above the stratum 2 the usual packer 7 is installed.

The packer 7 is located between the two gas-bearing strata, and, in conjunction with the tubing 5, the packer serves as a seal in the bore 55 of the well, whereby the sole escape of the gas

yielded by the second sand 2 is by way of the tubing 5, while the escape of the gas from the upper sand is by way of the passage 8 that lies between the tubing 5 and the outer casing or wall of the well. At the surface the two streams 5 of gas may be fed into a common main, or they may be carried in independent lines. With such details of common practice, however, the invention is not immediately concerned, and I shall not dwell further upon them, other than to mention 10 that the top of the inner tubing 5 is equipped with a gate valve 9 which, when opened, establishes communication with the atmosphere.

In the field the vertical distance between two subterranean gas-bearing strata may vary from 15 a few feet to several hundred feet, and in exemplary way the interval between the strata 1 and 2 is given as two hundred and fifty feet. In such case, the packer 7 is installed from fifty to one hundred feet above the sand 2, and the 20 interval from the sand 1 to the packer is from one hundred and fifty to two hundred feet.

Between the packer 7 and the upper sand 1, I organize in the tubing 5 an expandible drainage coupling 10, and conveniently the coupling 25 10 lies from fifty to one hundred feet above the packer.

The expandible coupling 10 includes a head 11 which is secured in threaded union 12 to the lower end of the upper portion of the tubing that reaches from the coupling to the mouth of the well. The external wall of the head 11 is provided with circumferential serrations or "slip" rings 11a, whereby the coupling may be grappled with fishing tools in case it be "lost" in the well. 30 The head 11 carries a cylinder portion 13 which includes a circumferentially extending line of relatively small orifices 14, and within the cylinder portion 13, a plunger 15 is organized. The plunger is formed with an annular shoulder 15a, 40 and a keeper 16 secured in the lower end of the cylinder portion 13 serves, in cooperation with such shoulder, to secure the parts in assembly; from within the cylinder portion 13, the plunger continues downward in a tubular extension 15b 45 which is connected, by an ordinary coupling 17, to the upper end of the lower portion of tubing 5 that extends from coupling 17 downward to the bottom of the well. As the drawing indicates, the head 11 and plunger 15 are hollow, providing in conjunction with the tubing 5 a continuous passage from the bottom of the well to the top—a passage which normally is sealed from and independent of the outer passage (8) within which it extends.

Within the cylinder portion 13, the head 11 of the coupling is provided with an upwardly and inwardly tapering seat 11b, and, advantageously, the seat is provided in an inset block 11c. 5 The plunger 15 is formed of a relatively non-corrodible metal, such as brass or bronze, and the block 11c is formed of a cuprous, nickel alloy, such as is commonly known as monel metal. Otherwise, the coupling may be formed of cast 10 iron or steel. The upper or inner end of the plunger 15 is conical, providing a tapered face 15c adapted normally to engage the seat 11b, and, as shown in Fig. I, when such normal condition prevails, the body of the plunger closes the ori- 15 fices 14 from within. In the alternate or un-seated position of the plunger, the ports 14 are uncovered.

In normal operation the lower end of the tubing 5 rests upon the bottom of the well; subject 20 to the weight of the tubing 5 above, the head 11 of the coupling bears in seated position upon the upper, tapered end of the plunger 15, and accordingly the orifices 14 are closed, as shown in Fig. I. The water or oil draining from the sand 25 2 collects in the bottom of the well and in the bottom portion 50 of the tubing 5; when the liquid rises to such level in the well as to retard unduly the yield of the sand, a bailer is lowered in the tubing 5 and is operated in well-known 30 manner to remove the liquid.

The liquid seeping from the upper sand 1 drains into the bore of the well above the packer 7, and is separated from the gas yielded by said upper sand and flowing upward through outer 35 passage 8. The packer serves normally to prevent such liquid from running to the bottom of the well and flooding the second sand 2. The liquid is collected in passage 8 between the sand stratum 1 and the packer. During the continued operation of the well, the liquid collected 40 in passage 8 gradually increases in volume and, unless it is removed, it eventually reaches and floods the upper sand, in such manner as to retard or throttle the yield of stratum 1. As has 45 been already mentioned, the problem in mind involves the removal of this so-called upper liquid.

In removing such liquid, the casing head gland 6 is released or set ajar, and the usual anchor 50 rods (not shown) are loosened; the valve 9 is opened, causing the high-pressure gas from the second sand 2 to flow violently upward through the tubing and to discharge into the open atmosphere (or into a suitable closed receiver); 55 then the tubing 5 is elevated a few inches and stayed, whereby the head 11 and the cylinder portion 13 of the coupling 10 are moved upward relatively to the plunger 15; and thus the seat 11b is removed from the conical face 15c of the plunger, and the orifices 14 are uncovered, as indicated in Fig. II. In consequence the liquid, which is confined above the packer 7, is caused to spurt inwardly through the orifices 14, whereupon it is entrained in the gas flowing upward through 60 the tubing 5. The gas carries the entrained liquid to the top of the well where it is discharged through the open valve 9. Operation is continued until no liquid appears in the discharged gas, and this condition indicates that 65 the level of liquid in the passage 8 and above the packer 7 has lowered to the line of orifices 14. Thereupon, the tubing 5 at the top of the well is released and lowered; the coupling head 11 drops back into seated position upon the 70 end of the plunger 15, and the orifices 14 are

closed; the casing head gland 6 is tightened, the valve 9 is closed, and normal operation of the well is again conducted. Thus, it will be understood that the normal operation of the well may be interrupted from time to time, and the liquid draining from the upper sand 1 may be removed in the above-described manner. Of course, the vertical interval between the coupling 10 and the packer 7 is always flooded, but this condition does no harm—indeed it is desirable, inasmuch as it advantageously provides a pool in which solid particles of sand or other material entering the passage 8 may settle below the orifices 14. That is to say, particles of solid matter will not enter the coupling and interfere with 10 tight seating of the plunger. 15

It will be observed of my expandible coupling that, when the ports 14 are uncovered, a region R is afforded between the seat 11b and the face 15c of the plunger; this region R comprises a 20 passage which is inclined upward, toward the course of gaseous flow within the tubing 5, whereby the gas streaming through the coupling produces a substantial aspirating effect. The orifices 14 are relatively small, and, when brought 25 into play, they squirt relatively fine streams of liquid into the region R. Due to the relatively small orifices and such aspirating effect, the liquid spouting into the coupling is broken up 30 into small globules which are readily entrained with and carried upward by the flowing gas. 35

It has been found that the inwardly spouting liquid, in washing over the tapered surface 15c of the plunger and the tapered surface 11b of the block 11c, serves to cleanse the surfaces of such dirt and grit as normally tend to collect thereon, whereby, when the upper section of tubing is again lowered, to close the orifices 14, a snug engagement of the surfaces (11b, 15c) is insured. 40

I have found in a practical installation that, when the outer casing 3 comprises six inch pipe and the inner tubing 5 comprises two inch pipe, the orifices 14 may be four in number, and each may be $\frac{1}{8}$ of an inch in diameter. 45

It may so happen that the pressure of the gas yielded by the lower sand 2 is insufficient to produce the necessary energy to carry the entrained liquid to the top of the well. In such case the liquid entering the coupling is allowed 50 to collect at the bottom of the tubing 5, whence it is removed by a bailer in the usual way.

It will be understood that no special tools or rods need be run down the well, to open or close the orifices 14. The manipulation of the upper 55 reach of the tubing 5 is all that is required.

I contemplate that my expandible coupling may be used in a water well which is fed by two or more water-bearing strata. When the lower stratum runs dry, the coupling may be expanded, to feed water from the upper stratum into the well tubing. And, additionally, the coupling may be employed with advantage in multiple strata oil wells, or wells having an oil stratum and a gas stratum. 60

I claim as my invention:

A coupling for joining upper and lower sections of well-tubing, said coupling comprising a head for attachment to the end of one of said sections of tubing, a passage extending through 70 said head and adapted to communicate with the bore of said section of tubing, a tapered seat of special material embodied in said head adjacent to one end of said passage, a cylinder portion integrated with and extending from said head, said 75

- cylinder portion being of greater radial extent than said seat, a hollow plunger adapted to be secured to the end of said other section of tubing and to comprise a continuation of the bore 5 thereof, said plunger extending into said cylinder portion and including a conical end cooperating with said seat, said plunger including a shoulder within said cylinder portion, and means carried by said cylinder portion and cooperating with 10 said shoulder to secure the parts in assembly, the taper of said seat and the conical end of said plunger being inclined upward and inward rela-
- tively to the axis of the coupled sections of tubing, whereby, by moving said upper section of tubing relatively to the lower, the tapered seat moves from said conical end and forms an upwardly inclined aspirating passage communicating with the bore of the tubing assembly, and said cylinder portion including an inlet port normally closed by said plunger and communicating with said aspirating passage when said upper section of tubing is moved, as described. 10
